UNITED STATES PATENT OFFICE.

WILLIAM PISKURAN, OF ELYRIA, OHIO.

SHOEMAKER'S JACK.

1,383,421.

Specification of Letters Patent.

Patented July 5, 1921.

Application filed December 6, 1919. Serial No. 342,998.

To all whom it may concern:

Be it known that I, WILLIAM PISKURAN, a citizen of the United States, and a resident of Elyria, county of Lorain, and State of Ohio, have invented certain new and useful Improvements in Shoemakers' Jacks; and I do hereby declare the following to be a full, clear, and exact description of the invention, such as will enable others skilled in the art 10 to which it appertains to make and use the same.

This invention relates to jacks for repairing boots and shoes, and one of the objects is to construct a jack of light weight and reduced dimensions, without detracting from the usefulness and efficiency of the same.

Another object is to provide a removable last that fits exactly the shoe undergoing repair.

20 A further object is to provide means for the removing of the tight-fitting last.

Further objects will appear in the appended description.

The usual shoemaker's jack has a last that 25 can be used on either the right or the left shoe, and it is of such design and shape as to fit shoes of a certain range of sizes. However, it fits no size of shoe even approximately, and it is necessary in nailing on 30 soles to push the shoe from one side to the other as the nails are driven in. The lasts also have a very blunt point, so that they cannot reach up into the usual shaped shoe. The tacks, therefore, which are driven into 35 the tip of the toe, do not strike the last and consequently, they are not clenched over, but are retained in place only through friction.

In my improvement I have employed a 40 plurality of lasts that may be readily placed on the last supports, and each of these lasts is shaped to fit a particular size and style of shoe, so that a shoemaker by having a complete set of the lasts can attach the correct one to a last support and can then nail 45 the sole on the shoe without taking any pains to shift the shoe around where the tack will hit the last. The metal last on the last support makes a tight fit therewith throughout the inside of the shoe and all of the 50 nails can be clenched in place without taking any pains whatever. I also proportion the jack in such a way and use reinforcing members in such position as to produce a very light weight article, that is exceedingly 55 strong and simple in operation.

Referring to the drawings:

Figure 1 is a side elevation of a shoemaker's jack.

Fig. 2 is a front elevation of the jack, with the last support rotated ninety degrees 60 from the position shown in Fig. 1, the metal last also being removed.

Fig. 3 is a plan of the metal last.

Fig. 4 is a section taken on the line A—A of Fig. 2.

Fig. 5 is a plan view of the upper supporting member of the jack and a portion of the standard, the last being removed.

Referring to the drawings, the jack has a vertical standard 1 joined to a base 2. In 70 the rear is arranged a web 3 integrally joined to the base 2 and the back of the standard. The standard is, in the main, of channel bar shape, as will be evident from an inspection of Fig. 4. The back portion 75 4 of the channel-shaped standard has a slot 5 with a reinforcing web 6 around it, one of the webs having a plurality of ratchet teeth or notches 7 to engage a prong on the foot lever 8 pivoted at 9 to the web 3. 80

The upper part of the standard has a somewhat enlarged top 10 with a couple of upstanding ears 11 in which is hinged an L-shaped support 12 having an internal cavity 13 for lightness and for passage of 85 a holding strap, later referred to. The support has a socket 14 receiving a post 15, so that the latter may turn freely therein. A set screw 16 fits into a groove 17 in the lower part of the post, so that it may turn freely, 90 but yet cannot be removed without loosening the set screw. On the horizontal portion of the L-shaped support is arranged a rod or bar 18 having a tip 19 adapted to fit into the metal shoe last for purposes of removal, as later described. The post 15 is made hollow, and has an opening, such as 20, on each side. The cavity in the upper part of the post may be made slightly tapering to receive the projection 21 of the last 100 support 22, the construction preferably being such that the last support may be turned into any desired position for the convenience of the shoemaker.

The last support 22 is not shaped to fit 105 the shoes, but is arranged to have a removable last 23 placed thereon. Any means may be employed for detachably fitting the last to the last support, but, by way of example, I have shown a ridge 23' adapted 110

to fit in the groove 24 in the last. The front part of the last support is preferably shortened at 25, and the last has a projection 26 on the toe portion that fits against this end of the last support. Each last is shaped to fit a particular style and size of shoe, and there will be a plurality of them with each outfit, all having the lower portion shaped to fit the top part of the last support 22, and the last support being made small enough to accommodate a number of the lasts without projecting beyond the sides. Of course, with a large number of lasts more than one last support may be used,—probably three last supports in each outfit will be sufficient, one being very small in size, the other intermediate, and the third, of large size. The last is preferably left free to move in a direction at right angles to the plane of the paper in Fig. 1, as this permits the shifting of the last from side to side, in case it does not quite fit the shoe.

The upper portion of the standard 1 preferably has a resilient pad 27 of leather or wood, against which the forward portion of the support 12 is adapted to rest when in operative position. This reduces the jar when the nails are being driven into the shoe, and relieves the jack of the strains from the blow of the hammer. Since the standard is pivoted at 28 in the ears 11, it can be readily turned over to the left (Fig. 1), whenever desired, for trimming the edges of the sole, which operation can be more readily performed in this position, and since the pivot 14 is above the hinge 28, the operator can turn the shoe from side to side in trimming the sole. This is a material advantage.

A strap 29 is secured to the foot lever 8 and passes upward between the side webs of the standard 1 through a passage 30 at the back of the upper portion of the standard around the pivot 28 and upward through the cavity 13 of the support to a point adjacent the openings 20 in the post 15. A loop 31 is passed over the upper part of the last and last support, and extends through the openings 20, where it joins the upper part 50 of the strap 29.

In repairing a shoe, the shoemaker will pull the loop 31 off of the last and last support by releasing the foot-lever 8 from the catches 7, the return of the lever being facilitated by a spring 32, if desired. The proper size and shape of last will then be selected and placed on top of the last support. The shoe is then placed over the last and last support and the loop 31 placed back over the shoe. The treadle 8 is then depressed by the foot and the strap pulls 60 tightly down on the shoe and holds it securely in position. The shoemaker can then drive the nails into the shoe sole without manipulating the shoe, as the metal last 23 65 fits the shoe, and each nail driven in will find metal beneath it to clench the point in position.

When the shoe sole has been nailed on and the shoe is to be removed, the reverse operations will be performed, except that the metal last will remain inside the shoe, as it tightly fits it. To remove the metal last, the shoemaker will place the point 19 of the post 18 in the cavity 33 and the shoe is tipped 75 forward and drawn off of the last.

Having described my invention, what I claim is:

In a cobbler's jack, a channel-shaped standard, a base attached to the standard, said standard having a vertical slot adjacent the base, a reinforcing web around said slot, a plurality of teeth in the side of said web, a lever pivoted adjacent to said base and having a catch adapted to engage said teeth, a hollow L-shaped support hinged to said standard at the top, a hollow post detachably secured to said support and adapted to rotate therein, said post having openings in two sides, a last support fitted to said post, a last detachably secured to said last support, a strap extending from said lever to a point adjacent said openings, and a loop extending from the strap through said openings and adapted to pass over a shoe placed 90 on said last and last support.

In witness whereof, I have hereunto signed my name this 3rd day of December, 1919.

WILLIAM PISKURAN.
